UNITED STATES PATENT OFFICE.

GEORGE W. WALLACE, OF SAN FRANCISCO, CALIFORNIA.

METHOD OF CARBONIZING FUEL.

Application filed May 24, 1926. Serial No. 111,391.

This invention relates to methods of carbonizing fuel; and it comprises a process of forming and removing volatilizable constituents from fuel by low temperature carbonization, with recovery of valuable by-products and the production of smokeless fuel or coke wherein the material to be carbonized which is usually bituminous coal but which may be lignite, wood or other fuel normally burning with production of flame and smoke, is pushed through a relatively short chamber, usually substantially horizontal and sometimes slightly tapered and in the nature of a conduit, as a full area moving charge with feed of material at one end, which is maintained at a relatively low temperature and with removal of carbonized fuel at the other end, which is at a high temperature maintained by impingement of flame on said charge end, flame gases being moved through the column in countercurrent whereby a relatively stationary zone of low temperature carbonization is instituted and maintained, and the fuel discharged from the hot end is cooled and collected; all as more fully hereinafter set forth and as claimed.

Bituminous coal contains a large proportion of hydrogen in the form of hydrocarbons and by appropriate heating methods, as is well known, gas and oily products can be obtained. In ordinary gas making operations, carbonization is at a high temperature and the evolved vapors are further broken down by the heat to a large extent. The net result is an increase in the amount of gas and a decrease in the amount of oils; these latter being of the aromatic or coal tar type. Incidentally, high temperature carbonization gives a greater yield of carbon. It is therefore resorted to in most coke making processes. By carbonization at lower temperatures with immediate removal of distillation products from the hot zone the character of the products is quite different. There is less gas and more condensable liquid. With many coals, oil shales and lignites, this liquid has petroleum characteristics. The liquid contains various oils and tars which have, generally speaking, a commercial value depending on their volatility; the more volatile components are worth more than the less. In low temperature carbonization the fixed carbon formed is smokeless to an extent depending upon the thoroughness of the carbonization.

Smokeless fuel formed in this way is desirable as a fuel for domestic and manufacturing processes. It may be regarded as a product intermediate the original coal and a true coke. In making smokeless fuel it is usual to employ low temperature carbonization and endeavor to effect a sort of rough fractionation, forming and removing only the more volatile products.

The present invention relates to a process of effecting low temperature carbonization with formation of smokeless fuel or coke, as may be desired, with concomitant production of liquid byproducts. These products may be wholly those of low temperature carbonization or may contain some amount of the aromatic hydrocarbons characterizing high temperature distillation. The process is flexible in this respect; it being possible by slight variation of conditions to obtain products which have undergone secondary decomposition with an increase in the amount of fixed carbon and production of aromatic oils. The action requires a certain length of time and if this time be afforded and only enough heat supplied to keep the action going with all the vapor products at once removed to a cooler zone, nothing is formed but low temperature products. With bituminous coal low in oxygen, oils of petroleum character are formed. The coke formed however is of loose friable character. By cutting the time short, by not removing all the vapors and by other variations of conditions the results are varied. To a certain extent the amounts of condensable oily products formed and of fixed carbon are reciprocal; the more of one the less of the other.

In most methods of carbonization heat is passed through the material by conduction in some way, as in the use of the ordinary gas retort. In the present invention heat is applied as the sensible heat of hot gases passing through the material, the material and the gases traveling in countercurrent. In so doing I am enabled to take advantage of the exothermic actions in carbonization.

With coal and most organic materials carbonization is exothermic; that is, if the materials be brought to a certain reaction temperature they break down spontaneously with liberation of heat; the amount of this heat being enough to form the gases and vapors which are the products. Sometimes the exothermic action is masked by endo-

thermic actions and in any event, the actual amount of heat developed, and consequently the temperature attained, is the algebraic sum of the true carbonization heat, radiation losses, heat employed in bringing mineral matters (ash) to temperature, heat consumed in vaporizing moisture, etc. etc. The net result varies with the various materials but with most the action is positively 10 exothermic, and with proper apparatus will keep itself alive.

In the present invention I institute and maintain a moving pervious column, usually substantially horizontal, with one end relatively cold and the other end at as high a temperature as it can be given by contact with flame burning in an arch just above; the flame gases passing inward and forward through the moving material toward the 20 cold end. Ordinarily, a flame of burning gas is usually somewhere around 1800—2000° F. Flame gases at this temperature, however, in passing through hot carbonized material drop automatically just beyond the 25 impingement face to 1400—1500° F. by the endothermic reduction of CO_2 and H_2O . Such a temperature is attained inside the column whatever the temperature of the flame gases may be. As so far stated, my 30 moving column has a relatively low temperature at one end and at point near the other end has a temperature of 1400—1500° F.; with a discharge face just beyond it at a higher temperature. Under these 35 conditions a certain temperature gradient is established and maintained within and along the column. At the point where the flame gases are reduced, a fixed temperature is established and maintained, with temperatures 40 declining therebeyond to the temperature at the point of feed. The gradient however is never a straight line and the shape of the actual curved depends, among other things, upon the rate of feed of the particular fuel 45 treated. There is always however an intermediate zone at another rather fixed temperature, that of carbonization, which is generally around 800° F. In this zone the curve of temperature gradient is usually 50 rather flat. The fuel passing forward is first dried and preheated and then undergoes spontaneous carbonization with development of heat. Beyond this point the carbonized material is heated up to increasing 55 temperatures till it takes the temperature fixed by the endothermic reduction of CO_2 and H_2O . Operating as described, all the actions I desire can be accomplished in a relatively short cylindrical chamber; this 60 chamber ordinarily not having a length exceeding 3 or 4 times its diameter. In handling several different coals with an 18 inch horizontal cylindrical reaction chamber of conduit form with a moving full area 65 column of material, all the actions I desire

were accomplished within the length of 32 inches; sometimes within the length of 24 inches. However with certain materials containing considerable moisture, such as peats and certain lignites, the chamber can 70 be advantageously lengthened somewhat at the cool end to reduce heat losses in evaporating moisture. With nearly any fuel the carbonization zone is quite short; all the carbonization is accomplished within a few 75 inches and the material passed beyond is, or may be, substantially free of volatiles and with all the gases and vapors passed immediately forward toward the cold end of the apparatus, there is no chance for secondary 80 decomposition. With cold incoming materials the temperature at the feed end is often around 212° F. Frequently, condensation of moisture maintains this particular temperature at this point. Lignites sometimes 85 carry as high as 40 per cent moisture which requires a considerable expenditure of heat to remove by vaporization; that is by ordinary drying. Evaporation of a pound of water requires several times as many B. t. u. 90 as are needed to bring it to 212° F. from the ordinary temperature. In applying the present invention to lignite some water is evaporated in the drying zone but the heat consumed is restored by condensation in the 95 cooler zones beyond and by lengthening the conduit toward the feed end and giving it a slight downward inclination the hot water flows backward against the oncoming material, exchanging heat with it. The net result is the removal of much of the water of the peat or lignite as a flowing stream at a 100 comparatively low temperature. With a horizontal chamber, if it be given a slight inclination toward the feed end, this not only 105 facilitates removal of condensed water but that of liquid products of distillation. With such a positive removal of heavy 110 liquids (tars, etc.) the conditions in the carbonizing zone are affected materially; there is much less opportunity for secondary carbonization to occur. Conversely, if the chamber be given a tilt in the other direction, condensed heavy tars drain back 115 toward the carbonization zone and there is a production of secondary carbon, increasing the amount of solid fuel formed and materially changing its character. With this formation of secondary carbon comes a 120 change in the oily products.

With the feed end of the reaction chamber sharply inclined toward the carbonization zone tarry products pass in that direction to a grater or less extent and the resultant solid fuel is more of a coky material. By varying the inclination I can in fact produce various gradations between a true coke and a fuel which is simply, so to speak, de-smoked.

With various changes in these two factors 130

I can produce varying results. Assume for example, that I desire to make a coke-like fuel from an ordinary type of lignite high in volatiles and in water but not containing enough fusible matter to make a coke by ordinary heating. By giving the conduit a downward slant toward the feed end with an angle and short downward slant beyond to the carbonizing zone, the water and much of the volatile matter pass on beyond the angle in the way previously described. But some high boiling tars condensing at high temperatures drain back and are carried back to the carbonizing zone and recarbonized there, at least to some extent. If further, the feed be forced so that the end of the carbonizing zone, which otherwise is usually fairly definite, merges with the high temperature zones beyond, the secondary carbon is hard and firm and cements the carbonized material into a coke.

The present invention is applicable to bituminous coal, lignite, brown coal, oil shale and the like. It may also be used with wood and similar vegetable materials, such as straw, sawdust, peat, etc. With vegetable materials, however, the vapors formed are of acid nature and acid resistant material should be used at the feed end. With mineral fuels, the vapors are alkaline because of the presence of ammonia, and iron and steel can be used. In this connection it may be noted that the present process gives excellent yields of ammonia. In obtaining high yields of ammonia, it is desirable to supplement the operation as so far described, by a short treatment of the carbonized material under regulated gas producer conditions.

In practicing the present invention, the nongaseous products obtained by distillation are partly condensed in the material and may be drained off, but in part they go forward as vapors with the fixed gases. Because of the presence of vapors of light oils in the fixed gases, it is in general advisable to scrub as well as cool in treating emerging gases for their recovery.

In the accompanying illustration I have shown more or less diagrammatically certain apparatus useful in performing the process of the present invention. The showing is a central vertical section, with some elements in elevation.

In the showing, element 1 is a reaction chamber which takes the form of a relatively short wide conduit. It may be made of metal or refractory material. Brick lined metal casings are satisfactory. At the cold end 2, it is supplied with solid fragmentary material by any suitable stoking mechanism. This material is usually at the ordinary temperature. It may however be warmed or preheated. Warm materials coming from driers are sometimes used. I have illustrat-

ed a feed device consisting of a cylinder 3 provided with reciprocating plunger 4 actuated by suitable means 5. Material is supplied to this feed device from chute 6. At this end of the reaction chamber is provided a drain outlet 7 and vapor and gas outlet 8; the latter communicating with suitable condensing and scrubbing means as well as suction means, not shown. I also provide the conduit with pipe 9 serving for the introduction of water or steam where moistening or cooling is desirable. Within the conduit the material moves forward as a full area column. The column may be regarded as passing through three zones which I have marked A, B and C respectively. In zone A the material is dried and preheated. At the end 2 of the apparatus the material is frequently moist or wet because of condensation of moisture. The dried preheated material moving forward in zone A attains a temperature at which spontaneous carbonization sets in with production of carbonization zone indicated as B. With a feed not above a certain speed for each particular material, the boundaries of B are quite sharp and definite. At a somewhat higher rate they merge more or less into the other zones. Sometimes I desire them definite; sometimes not.

Beyond B the material travels through zone C becoming hotter as it goes, until it reaches a quite definite temperature just inside the discharge face. With a horizontal reaction chamber, at the discharge end the material often has an angle-of-repose face 10; with the angle of course depending on the carbonized material. In making coke, the column breaks off at this face. Whether falling off or broken off, as shown material drops from this face into a vertical chamber 11. In this chamber it may be quenched or cooled. Sometimes I blow draft currents of various kinds through it for one purpose or another, the draft current going in through pipe 12 which is provided with supply branch 13

14 and 15 which may serve respectively for air, products of combustion and steam. Any gas formed by the action of this draft current and not wanted in the operation is sent to a place of use through conduit 16. Usually here is more than enough gas produced to furnish the flame with the aid of air from 17; where this is not the case I provide burner pipe 17 which may be fed with gas recovered from the products going away through pipe 8. In so using gas, air may be fed in to form a flame by damper mechanism 18. The flame burns immediately below a heat radiating arch and the material coming from face 10 is also heated by radiation. Sometimes in using a draft current through 12 there is enough development of gas in chamber 11 to enable me to supply merely air through pipe 17, damper 18 being closed.

However developed the flame should be of re- 125

ducing character; there should be more than enough gas to burn with the amount of air admitted. However produced, flame indicated as 19 plays on the face 10 of the advancing column of material, and the flame gases from it pass forward against the movement of solid material. Carbonized fuel accumulating in chamber 11 is discharged continuously or from time to time. I have shown a "star feed" discharge element 20.

For quenching, water or steam is often employed and because of the temperature of the material discharged at face 10, considerable hydrogen and carbon monoxide are formed and aid in producing the required draft gases and increases the available surplus gas. This surplus gas may be used for other industrial purposes such for instance as raising steam in a power plant. In so doing the hydrogen and monoxide are reburnt at a high temperature, returning the heat to the face 10 and aiding in giving a high yield of ammonia.

In the operation of the described device, presuming soft coal is fed in through chute 6, the reciprocation of plunger 4 forces successive portions into chamber 1 through which it moves from right to left. The cold material coming in condenses water, tarry vapors, etc. and these drain off through outlet 7 for separation elsewhere. Uncondensed gases and vapors go to exit through 8. If the material is predried, the amount of moisture here may be merely that coming in with flame gases and with a large volume of such gases none may condense. If the material be wet at 2 it becomes dry in moving toward zone B and when its heat is sufficient it undergoes carbonization in B. Passing beyond B, the material is heated up progressively until it reaches a point just behind face 10 at which there is a tolerably sharp temperature gradient. Material falling off the end face usually has nearly the flame temperature. This material accumulates. Sometimes I pass a draft current through it to form a little gas; sometimes I do not. Usually I introduce at least a little moisture for quenching and gas forming purposes; and particularly where production of ammonia is a desideratum. The action of steam on hot carbon being endothermic, the use of a draft current containing steam is useful in cooling. In any event the accumulating material is finally cooled and usually quenched. It is removed from the collection chamber by the star feed shown. In the present invention I do not claim apparatus of the general type of that shown and described, this forming the subject matter of another and copending application filed May 18, 1925, Serial No. 31,148.

While I have shown the carbonizing chamber as of uniform cross section, the cross section may be different at different

points with fuels expanding or shrinking in the operation. In making compact coke-like fuels it is in general advantageous to have somewhat of a taper in the chamber; enough to give some resistance to the forced feed 70 means.

What I do claim is:—

1. In the production of coke or smokeless fuel and byproducts by carbonization the process which comprises establishing 75 and maintaining a moving substantially horizontal pervious column of fragmentary solid carbonizable material in a chamber of conduit form as a full area charge, one end of said column being formed by incoming relatively cool material, impinging a flame on the other end of said column and transmitting hot flame gases through said column in a direction counter to the passage of solid materials, whereby a stationary zone of carbonization is established and maintained. 80

2. In the production of coke or smokeless fuel and byproducts by carbonization the process which comprises establishing and maintaining a moving substantially horizontal pervious column of fragmentary solid carbonizable material in a chamber of conduit form as a full area charge, one end of said column being formed by incoming relatively cool material, impinging a flame on 85 the other end of said column and transmitting hot flame gases through said column in a direction counter to the passage of solid materials, whereby a stationary zone of carbonization is established and maintained and cooling and quenching material coming from the flame heated end. 90

3. In the production of coke or smokeless fuel and byproducts by carbonization the process which comprises establishing and 105 maintaining a moving substantially horizontal pervious column of fragmentary solid carbonizable material in a chamber of conduit form as a full area charge, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form 110 a hot accumulation and passing therethrough a draft current containing an endothermic agent so as to cool said mass with production of gas to aid in the formation of said flame. 115

4. In the production of coke or smokeless fuel and byproducts by carbonization the process which comprises establishing and 125 maintaining a moving substantially horizontal pervious column of fragmentary solid carbonizable material in a substantially horizontal chamber of conduit form as a full area charge, one end of said column being 130

- formed by incoming relatively cool material, impinging a flame on the other end of said column and transmitting hot flame gases through said column in a direction counter to the passage of solid materials, whereby a stationary zone of carbonization is established and maintained.
5. In the production of coke or smokeless fuel and byproducts by carbonization the process which comprises establishing and maintaining a moving substantially horizontal pervious column of fragmentary solid carbonizable material in a substantially horizontal chamber of conduit form as a full area charge, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form a hot accumulation and passing therethrough a draft current containing an endothermic agent so as to cool said mass with production of gas to aid in the formation of said flame.
10. In the production of coke or smokeless fuel and byproducts by carbonization the process which comprises establishing and maintaining a moving substantially horizontal pervious column of fragmentary solid carbonizable material in and occupying the entire cross-section of a substantially horizontal chamber of conduit form with a slight upward inclination toward the discharge end, one end of said column being formed by incoming relatively cool material, impinging a flame on the other end of said column and transmitting hot flame gases through said column in a direction counter to the passage of solid materials, whereby a stationary zone of carbonization is established and maintained.
15. In the production of coke or smokeless fuel and byproducts by carbonization the process which comprises establishing and maintaining a moving substantially horizontal pervious column of fragmentary solid carbonizable material in and occupying the entire cross-section of a substantially horizontal chamber of conduit form with a slight upward inclination toward the discharge end, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form a hot accumulation and passing therethrough a draft current containing an endothermic agent so as to cool said mass with production of gas to aid in the formation of said flame.
20. In the production of coke or smokeless fuel and byproducts by carbonization the process which comprises establishing and maintaining a moving substantially horizontal pervious column of fragmentary solid carbonizable material in and occupying the entire cross-section of a substantially horizontal chamber of conduit form with a slight upward inclination toward the discharge end, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form a hot accumulation and passing therethrough a draft current containing an endothermic agent so as to cool said mass with production of gas to aid in the formation of said flame.
25. In the production of coke or smokeless fuel and byproducts by carbonization the process which comprises establishing and maintaining a moving substantially horizontal pervious column of fragmentary solid carbonizable material in and occupying the entire cross-section of a substantially horizontal chamber of conduit form with a slight upward inclination toward the discharge end, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form a hot accumulation and passing therethrough a draft current containing an endothermic agent so as to cool said mass with production of gas to aid in the formation of said flame.
30. In the production of coke or smokeless fuel and byproducts by carbonization the process which comprises establishing and maintaining a moving substantially horizontal pervious column of fragmentary solid carbonizable material in and occupying the entire cross-section of a substantially horizontal chamber of conduit form with a slight upward inclination toward the discharge end, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form a hot accumulation and passing therethrough a draft current containing an endothermic agent so as to cool said mass with production of gas to aid in the formation of said flame.
35. In the production of coke or smokeless fuel and byproducts by carbonization the process which comprises establishing and maintaining a moving substantially horizontal pervious column of fragmentary solid carbonizable material in and occupying the entire cross-section of a substantially horizontal chamber of conduit form with a slight upward inclination toward the discharge end, one end of said column being formed by incoming relatively cool material, impinging a flame on the other end of said column and transmitting hot flame gases through said column in a direction counter to the passage of solid materials, whereby a stationary zone of carbonization is established and maintained, discharging the flame heated mass to form a hot accumulation and passing therethrough a draft current containing an endothermic agent so as to cool said mass with production of gas to aid in the formation of said flame.

In testimony whereof, I have hereunto affixed my signature.

GEORGE W. WALLACE.
